UNITED STATES PATENT OFFICE.

WILLIAM NELSON, OF BROOKLYN, NEW YORK.

COMBINATION TABLE AND IRONING BOARD.

Application filed September 11, 1922. Serial No. 587,287.

To all whom it may concern:

Be it known that I, WILLIAM NELSON, a citizen of the United States, residing at Brooklyn, in the county of Kings and State of New York, have invented new and useful Improvements in Combination Tables and Ironing Boards, of which the following is a specification.

In carrying out the present invention it is my purpose to provide a combination table and ironing board wherein the ironing board may be arranged beneath the top of the table in an out of the way position when not in use and pulled out from beneath the table top and held in its outward position spaced apart from the adjacent edge of the table top when it is desired to use the same.

It is also my purpose to improve and simplify the general construction of devices of the class described and to provide a combination table and ironing board which may be manipulated and sold at small cost and which will embody comparatively few parts and this so arranged and correlated as to reduce the possibility of derangement to a minimum.

With the above recited objects in view and others of similar nature, the invention resides in the construction, combination and arrangement of parts hereinafter set forth in and falling within the scope of the appended claim.

In the accompanying drawings:—

Figure 1 is a perspective view of a table or cabinet constructed in accordance with my invention.

Figure 2 is a top plan view showing an ironing board withdrawn.

Figure 3 is a sectional view on the line 3—3 of Figure 2 showing the ironing board withdrawn.

Figure 4 is a similar view showing the ironing board beneath the table top.

Figure 5 is a cross sectional view through the end of the cabinet remote from the end shown in Figure 3.

Figure 6 is an enlarged fragmentary sectional view taken upon the line 6—6 of Figure 2.

Referring now to the drawings in detail, 1 designates a table which in the present instance is in the form of a cabinet comprising a top 2 and legs 3 connected to the top 2 at the corners thereof and holding the latter at the proper elevation. This cabinet is

provided with side walls 4 and with a rear wall and spaced apart from one of the side walls a short distance therefrom is a vertical partition 5 that lies parallel with the side wall and acts to provide a comparatively narrow chamber 6 and a relatively wide chamber in which latter are slidably mounted drawers 7 arranged one above the other.

Connected to the confronting surfaces of one side wall 4 and the partition 5 forming the chamber 6 are horizontal guide rails 8, 8 which in the present instance are arranged in superposed relation at opposite sides of the chamber, as clearly shown in Figure 6 of the drawings. Within the upper portion of the chamber 6 is a supporting block 9 having the side walls thereof formed with longitudinal grooves 10 that receive the guide rails 8, 8, respectively, so that the block 9 may be moved into and out of the upper portion of the chamber 6. The lower portion of the chamber 6 provides a compartment in which drawers may be mounted or which may be closed by door as desired.

The upper surface of the block 9 at a point approximately on the transverse center line thereof is formed to provide an abrupt shoulder 11 and in advance of the shoulder 11 is formed a depression 12 while the forward portion of the block in advance of the depression 12 is cut down so as to be of less thickness vertically than the corresponding dimension of the rear portion of the block behind the shoulder 11, as clearly illustrated in Figures 3 and 4 of the drawings. In this forward portion of the block immediately in advance of the depression 12 is fastened one end of an ironing board 13 that is arranged at right angles to the block and is rigidly fixed thereto so as to slide in and out with the block. This ironing board when moved beneath the top 2 of the cabinet lies between the under surface of such top and the top of the uppermost drawer 7, while when the block is pulled outwardly on the guide rails 8 the ironing board is spaced apart from the adjacent edge of the cabinet top as clearly shown in Figures 2 and 3 of the drawings so that it may be readily and conveniently used.

Depending from the under side of the top 2 of the cabinet adjacent to the forward edge thereof is a flap 14 which closes the space between the top 2 and the top of the uppermost drawer 7 when the ironing board

is beneath the table top as illustrated in Figures 1, 4 and 5 of the drawings thereby concealing the ironing board. When it is desired to pull the ironing board from beneath the top of the cabinet the flap 14 is swung upwardly and the block withdrawn. When the ironing board is in the positions shown in Figures 2, and 3 of the drawings, the flap 14 lies in the depression 12 against the shoulder 11. The free end of the ironing board 14 when beneath the table top rests upon a support 15 that is fastened to the adjacent side wall 4 of the cabinet.

From the foregoing description taken in connection with the accompanying drawings, it will be seen that I have provided a combination table or cabinet and ironing board wherein the ironing board may be readily and conveniently moved into and out of active position and wherein the ironing board when in active position will be disposed beneath the top of the cabinet and concealed from view.

I have entered into a detailed description of the construction and relative arrangement of the parts embraced in the present and preferred embodiment of the invention in order to impart a full, clear and exact understanding of the said embodiment. I do not desire, however, to be understood as confining myself to the specific construction and relative arrangement of parts inasmuch as in the future practice of the invention various changes and modifications may be made

such as fall within the scope of my invention 35 as defined in my appended claim.

Having described my invention, what I claim and desire to secure by Letters-Patent is:—

The combination with a cabinet including 40 a top supporting legs and side walls, of a vertical partition adjacent to one of said side walls dividing said cabinet into a narrow chamber and a relatively wide chamber, 45 guide rails on the confronting faces of said partition and the adjacent side wall, a block mounted upon said rails and capable of movement into and out of position beneath the top of said cabinet and an ironing board fixed to the upper surface of said block at 50 the forward portion thereof and movable to a position beneath the cabinet top when the block is moved inwardly and to a position beyond the cabinet top when the block is pulled outwardly, and a flap pivoted to the 55 underside of said top and designed to conceal said ironing board from view in inactive position beneath the cabinet top, the upper surface of said block at the transverse center line thereof being formed with an abrupt 60 shoulder and with a depression immediately in advance of said shoulder to provide a space for the reception of said flap when the ironing board is pulled outwardly whereby said flap may be maintained in its normal 65 position when the ironing board is in use.

In testimony whereof, I affix my signature.

WILLIAM NELSON.
